UNITED STATES PATENT OFFICE.

HENRY ENGLEHART, OF ELMER, NEW JERSEY.

POOL-TABLE.

1,297,815.

Specification of Letters Patent. Patented Mar. 18, 1919.

Application filed June 20, 1916. Serial No. 104,757.

To all whom it may concern:

Be it known that I, HENRY ENGLEHART, a citizen of the United States, residing at Elmer, in the county of Salem and State of New Jersey, have invented new and useful Improvements in Pool-Tables, of which the following is a specification.

This invention relates to improvements in pool tables especially with reference to the provision of mirrors or reflectors under the cushion and arranged between the pockets to aid the players.

The invention consists in the arrangement and construction of devices, hereinafter described and claimed.

In the accompanying drawing:—

Figure 1 is a plan of a pool table provided with reflectors constructed and arranged in accordance with my invention.

Fig. 2 is a detail transverse sectional view of the same.

For the purposes of this specification, a pool table is indicated at 1, the base being shown at 2, the cushion at 3 and the usual pockets at 4.

In accordance with my invention I provide reflectors 5 which may be mirrors or may be reflectors of any suitable type and which are arranged under the cushion and between the pockets as shown.

A cue ball is indicated at 5' in Fig. 1, an object ball at 6, and a cue at 7.

Copies of this patent may be obtained for five cents each, by addressing the "Commissioner of Patents, Washington, D. C."

By the provision of the reflectors between the pockets, a player is enabled to see the reflection of a pocket upon one side of the 35 table, in one of the reflectors upon the opposite side of the table, so that the pocket into which the ball is to be bounced can be kept in sight at the time the shot is being executed, enabling the player to properly judge 40 the angle at which the object ball must strike the cushion in order to rebound and enter the pocket reflected in the mirror. Without the use of these reflectors, the 45 player must judge the angle prior to the execution of the shot, particularly if the cue ball is well in advance of the pocket into which the bank is to be made, so that in shooting position, the pocket is not in sight and the shot is made merely from the memory of the location of the pocket, due to the 50 previous judgment of angles. With the present invention, the pockets may be kept in sight until after the execution of the shot, so that the player will not have to depend 55 upon memory of either the location of the pocket or the point at which the object ball is to strike the opposite cushion.

Having described the invention, what is claimed is:

A pool table having reflectors under the cushion and between the pockets.

In testimony whereof I affix my signature.

HENRY ENGLEHART.
